CLAIM

The ornamental design for universal mounting bracket, as shown and described.

DESCRIPTION

FIG. 1 is a perspective view of a universal mounting bracket showing our new design;

FIG. 2 is a front view thereof;

FIG. 3 is a side view thereof, the opposite side being a mirror image of the side shown;

FIG. 4 is a top view thereof; and

FIG. 5 is a rear view thereof.

Fig. 1.

Fig. 2.
